UNITED STATES PATENT OFFICE.

WILBUR S. SHEPPARD, OF COLORADO SPRINGS, COLORADO.

DESIGN FOR AN ELECTRIC HEATER.

44,942.

Specification for Design.

Patented Nov. 25, 1913.

Application filed August 27, 1913. Serial No. 787,028. Term of patent 7 years.

To all whom it may concern:

Be it known that I, WILBUR S. SHEPPARD, a citizen of the United States, residing at Colorado Springs, in the county of El Paso and State of Colorado, have invented a new, original, and ornamental Design for Electric Heaters, of which the following is a specification, reference being had to the accompanying drawings, forming a part thereof.

The figure is a perspective view of a heater showing my design.

I claim:

The ornamental design for an electric heater as shown.

WILBUR S. SHEPPARD.

Witnesses:

F. L. ROSSBACH,
A. E. YALE.
